UNITED STATES PATENT OFFICE

HENRY C. SCHIELD, OF MERRILL, WISCONSIN

DESIGN FOR A HAT STAND

Application filed May 20, 1932. Serial No. 43,858. Term of patent 7 years.

To all whom it may concern:

Be it known that I, HENRY C. SCHIELD, a citizen of the United States, and resident of Merrill, in the county of Lincoln and State of Wisconsin, have invented a new, original, and ornamental Design for a Hat Stand, of which the following is a specification, reference being had to the accompanying drawing, forming part thereof, in which—stand showing my new design, and Figure 2 is a side view of the same. The ring shown in the drawing is a permanent part of the hat stand and is not removable.

I claim:

The ornamental design for a hat stand, as shown and described.

Dated, May 3d, 1932.

HENRY C. SCHIELD.
